United States Patent Office

Des. 203,307

Patented Dec. 21, 1965

203,307

TYPEWRITER

Carl W. Sundberg, Bloomfield Hills, and Montgomery
Ferar, Huntington Woods, Mich., assignors to Sperry
Rand Corporation, New York, N.Y., a corporation of Delaware

Filed Mar. 12, 1964, Ser. No. 78,978

Term of patent 14 years

(Cl. D64—11)

FIG. 1

FIG. 1 is a front and right side perspective view of the typewriter embodying our new design;

FIG. 2 is a left side elevational view thereof; and

FIG. 3 is a rear elevational view thereof.

The essential features of the design reside in the portions shown in solid lines.

We claim:

The ornamental design for a typewriter, as shown and described.
